UNITED STATES PATENT OFFICE

128,401

DESIGN FOR A COLORIMETER OR THE LIKE

William F. Peck, Snyder, N. Y., assignor to Spencer Lens Company, Buffalo, N. Y., a corporation of New York

Application January 3, 1941, Serial No. 97,792

Term of patent 14 years

To all whom it may concern:

Be it known that I, William F. Peck, a citizen of the United States of America, residing at Snyder, in the county of Erie and State of New York, have invented a new, original, and ornamental design for Colorimeter or the like, of which the following is a specification, reference being made to the accompanying drawing, forming a part thereof.

Fig. 1 is a front perspective view of a colorimeter or the like, showing my new design; and

Fig. 2 is a perspective view of the back and opposite side of the same as shown in Fig. 1.

The characteristic features of the design are shown in full lines in the drawing.

I claim:

The ornamental design for a colorimeter or the like, substantially as shown and described.

WILLIAM F. PECK.
